UNITED STATES PATENT OFFICE.

AXEL GORD, OF GRANT PARK, ILLINOIS.

HAY-PRESS.

SPECIFICATION forming part of Letters Patent No. 338,592, dated March 23, 1886.

Application filed October 21, 1885. Serial No. 180,475. (No model.)

To all whom it may concern:

Be it known that I, AXEL GORD, of Grant Park, in the county of Kankakee and State of Illinois, have invented certain new and useful 5 Improvements in Hay-Presses; and I do hereby declare that the following is a full, clear, and exact description thereof, reference being had to the accompanying drawings, and to the letters of reference marked thereon, which 10 to form a part of this specification.

This invention relates to an improvement in hay-presses; and it consists in the matters hereinafter described, and pointed out in the appended claims.

15 The device herein shown as embodying my invention comprises, in connection with a hay-press proper, which is mounted upon wheels for convenience in transportation, a horse-power driving-gear especially adapted for actuating the press, as will hereinafter appear.

The invention may be more readily understood by reference to the accompanying drawings, in which—

Figure 1 is a plan view of a hay-press and 25 driving apparatus embodying my invention. Fig. 2 is a detail plan view of the horse-power driving-gear, certain parts thereof being removed to show portions beneath. Fig. 3 is a sectional view of the same, taken upon line 30 $\alpha\alpha$ of Fig. 2. Fig. 4 is a detail perspective of parts shown in Fig. 2. Fig. 5 is a side elevation of the hay-press proper. Fig. 6 is a longitudinal sectional view of the same, taken upon line $\alpha\alpha$ of Fig. 1.

35 In the said drawings, A indicates the frame or body of the hay-press; B B, the supporting-wheels, which are mounted upon axles B' B'', attached to the press, and C indicates as a whole the driving-gear.

40 The body A of the press is of the form generally of a rectangular box open at one end, and provided with a horizontally - reciprocating compressing piston or plunger, D, entering its open end, a door, E, at its top adjacent to its 45 open end for the insertion of the hay, and a side door, F, adjacent to its closed end for the exit of the compressed bale. The said piston or plunger is constructed to advance in compressing the bale to a point adjacent to the 50 edge of the door F, which latter is made of the same length and height as the compressed bale, so that the latter may be readily removed

when the said door is opened. The said door is desirably provided with a spring-latch, f, whereby it is held closed when shut, and may 55 be readily opened. The top door, E, is located in such position as to enable the hay to be deposited in front of the plunger when the latter is retracted, said door, in the operation of the device, being closed during the advance 60 movement of the plunger, to confine the hay at such time.

The top wall of the press at its portion opposite the door F, in which the hay is compressed, is preferably formed by a separate 65 movable piece or wall-section, G, sustained in position by pivoted links or arms g, so arranged that the said wall-section may be thrown and held downwardly when the bale is being compressed, and may be released and 70 allowed to rise or yield upwardly, so as to remove the pressure from the bale after the latter has been compressed. For this purpose, the links or arms g are arranged in an inclined position, as shown more clearly in Fig. 6, in 75 such manner that the wall-section will be carried downwardly by thrusting it endwise; and a device is provided for moving and holding the said section, consisting of a vertical rock-shaft, G', mounted upon the frame at 80 the end of the section G, toward which the latter moves when lifted, and provided with a laterally-directed arm or wing, g', adapted to engage a transversely-arranged projection, g'', upon the said section G when 85 the rock-shaft is rotated, the parts being so arranged that when the wing is engaged with the projection g'', and is at right angles with the latter, the said section will be held at the downward limit of its movement. The said 90 rock-shaft is also provided with an arm, g'', by which it may be actuated, said arm being conveniently operated by means of a cord, G'', attached to the end of the arm, and passing over pulleys G³ and G⁴ upon the frame, and 95 secured to the door F in such manner that when the door is closed the arm will be swung into position to force and hold the section G downwardly, and thus insure the bringing of the said section to place before pressure is applied to the hay. In this construction of these parts the rock-shaft will not be moved in the opening of the door, but the movable section 100 will be released by moving by hand the arm g''.

The inner walls of the press and the end of the plunger will be provided with the usual grooves, a , for the insertion of the bands or cords placed about the bale.

5 A reciprocatory movement is given to the plunger D in the machine shown by means of a vertically-arranged lever, H, pivoted at its middle part to frame-pieces A', extending outwardly from the body of the press adjacent to its open end, said lever H being connected at its upper end with the plunger by means of a connecting-rod, I, and at its lower end with the driving-gear through the medium of a rod, J.

15 The plunger D is, for lightness, desirably made hollow, the connecting-rod H being pivoted thereto at a point, h, within its hollow interior.

To facilitate the delivery of the hay to the press, the body A is preferably provided about the inlet-opening A², which is closed by the door E, with a wall, E', forming a hopper or receptacle, E², into which the hay may be thrown (while the plunger is advanced and the bale is being tied) preparatory to the next movement of the plunger, the latter being desirably provided with a top wall, d, of sufficient length to close the opening A² when the plunger is advanced, and thereby prevent the hay in the said receptacle from falling behind the plunger. It will of course be understood in this connection that the plunger will be moved backwardly a sufficient distance at each reciprocation to permit the hay within the receptacle E² to fall in front of said plunger, whereby a quantity of hay will be carried forward by the plunger in each advance movement of the latter.

The door E is, as before stated, kept closed during the forward movement of the plunger, a spring-latch, e, mounted upon the door and engaging suitable recesses or projections upon the frame, being preferably employed to hold it closed. In order to cause the said door to be opened automatically when the plunger has passed the opening A², so that hay may be thrown into the receptacle E² as soon as the plunger has passed the said opening, devices are provided as follows:

50 Pivoted upon the machine-frame at a point opposite the lever H is a rock-shaft, K, having bearings at its lower end upon one of the supports A' and at its upper end in an arm or bracket, A³, secured to the top of the frame.

55 Said rock-shaft is provided with a laterally-extending arm, K', to the outer end of which is attached a rope, k, extending over a pulley, k', mounted upon the top of the wall E' and attached at its opposite end to the spring-latch

60 e, these parts being arranged in such manner that when the arm K' is swung outwardly, so as to draw upon the rope k, the latch will first be disengaged by the action of the rope thereon, and the door E will thereafter be lifted and thrown into a vertical position. The rock-shaft is actuated for moving the arm K', as above set forth, by means of a short arm or

projection, K^2 , adapted for engagement with a projection or stop, H' , upon the lever H , the said stop and projection being relatively 70 so located that when the advanced face of the plunger has passed the opening A^2 the said stop will encounter the arm K^2 , and the door will be opened in the manner above described.

The driving-gear C for actuating the plunger 75 consists, generally, of a pivoted arm or sweep, L, mounted upon a suitable frame, C', and adapted in a familiar manner for the attachment of horses, whereby the arm may be swung about its pivot, said arm being constructed by 80 suitable operative connections to give a reciprocatory movement to the connecting-rod J, and, through the medium of the lever H, to the plunger. The sweep L is sustained in a horizontal position relatively to the other operative parts by means of a circle, C², upon which are mounted upon the said sweep and another upon a rigid arm or projection, L', attached thereto. The connecting-rod J is pivoted at 85 90 its outer end to a bar, J', which is in turn pivoted to a lever, J², having a bearing near one end upon the central stud or pivot, C³, upon which the sweep L is also pivoted. The lever J² is provided at its outer or free end, at 95 which it is connected with the bar J', with an upwardly-projecting stud or pin, j, extending into the path of a spring-detent, M, upon the sweep L, said detent, as herein shown, consisting of a sliding bar held in position for engagement with the stud j by means of a spring, m. Said detent is provided with a downwardly-extending part or projection, m', adapted for engagement with a stationary block or projection, e, upon the frame C', having an in- 100

clined surface constructed and arranged to throw the detent longitudinally, and to thereby release it from the pin j . These parts are so located that when the part of the sweep carrying the detent M is moving outwardly or away from the press the said detent will engage the stud j , thereby swinging the lever J^2 about its axis, the inclined stop c being arranged to encounter the said detent and to release it from the stud j when the said detent reaches the outward limit of its movement, or, in other words, when the sweep stands generally parallel with the connecting-rod J and the frame of the machine. In the particular construction illustrated the stud j forms, also, the pivotal connection between the bar J' and the lever J^2 ; but this construction is obviously not essential.

To carry backwardly the connecting-rod J after it has been moved in the manner described, the sweep L is provided with a second spring-detent, N, constructed in the same manner as the detent M, before described, and devised to engage a movable block, O, adapted to slide horizontally in grooved guides O' arranged upon the frame C' concentrically with the pivotal axis of the sweep. The said block is connected by means of a rope, o, passing over a pulley, O², with the end of the lever J² 125 130

opposite that in which the stud j is secured, the parts being so arranged that when the block O is moved with the sweep by the engagement of the detent N therewith, the end 5 of the lever J^2 to which the rope o is attached will be drawn outwardly so as to carry the opposite end of the lever and the bar J' and connecting-rod J in a direction opposite to that in which they are moved by the engagement 10 of the detent M with the stud j . The detent N is held in position for engagement with the block O by means of a spring, n , suitably applied for the purpose, and the said detent is released from the block at the forward limit 15 of the movement of the latter by an inclined or cam surface, O^3 , operating upon depending projection n' upon the said detent.

From the construction above described, it is entirely obvious that in the rotary movement 20 of the sweep about its axis the end of the lever J^2 carrying the stud j will be given an oscillatory movement, which is communicated to the lower end of the lever H by means of the bar J' and the connecting-rod J , through the 25 medium of which lever the desired reciprocatory movement is given to the plunger of the press.

In the operation of the devices described it is not contemplated that sufficient hay will be 30 inserted in front of the plunger to make a complete bale at one reciprocation thereof, but the plunger will be reciprocated continuously, and a quantity of hay placed in front thereof at each reciprocation until sufficient hay has 35 been forced into the press to make a bale of the desired size and weight.

In order to positively hold the plunger in its advanced position during the time that the compressed hay is being tied, a hooked detent, 40 P , is desirably pivoted upon the frame C' in position to engage the bar J' at the time that the said bar reaches the forward limit of its movement, the said detent preventing lateral movement of the bar when engaged with the 45 latter, and thereby holding the lever J^2 and the said bar from backward movement. To enable the said detent P to be readily disengaged, its portion p , back of its pivotal point, is desirably constructed to engage a stop, p' , 50 upon the sweep, so that in the further movement of the sweep after it has been stopped for the purpose of tying the bale, the detent will be released from the bar J and the latter allowed to move backward upon contact of the 55 detent N with the block O . In the particular construction illustrated the stop p' is formed by one of the supports or bearings of the detent M .

In order to prevent any relative movement 60 of the body of the hay-press and the frame C' under the operation of the driving-gear described, a brace, Q , is herein shown as extending between the said frame and the axle B' of the press. Said brace desirably consists of two 65 timbers, Q' , abutting at their outer ends against the frame C' , and resting at their inner ends

against downwardly inclined arms Q^2 , attached to the axle B' . The connecting-bar J is desirably located between the said timbers Q' , which latter are placed on edge for this purpose, and the space between the timbers is covered by planking q uniting the timbers and enabling the horses moving the sweep to readily pass over the timbers without liability of striking the said connecting-bar. 70

I claim as my invention—

1. The combination, with the walls of a hay-press provided with an outwardly-yielding section, G , of pivoted arms or links supporting said section, and a rock-shaft provided with a projection or wing engaging the section for holding it closed, substantially as described. 80

2. The combination, with the walls of a hay-press provided with an exit-door, F , and 85 with an outwardly-yielding section, G , of pivoted arms or links sustaining said section, a rock-shaft provided with a projection or wing engaging the section for holding it closed, and with an arm whereby said rock-shaft may be 90 moved, a cord connecting said door with the arm of the rock-shaft, and suitable guide-pulleys for the cord, substantially as described.

3. The combination, with a hay-press provided with an inlet-opening, A^2 , in its top, of 95 a door for closing said inlet-opening constructed to close by gravity, and provided with a spring-latch, a reciprocating plunger, a lever, H , connected with said plunger for actuating the latter, a vertical rock-shaft, K , provided with an arm, K' , and with an arm, K^2 , engaging the said lever H , a cord connecting the arm K' with the said spring-latch, and a guide-pulley for said cord, substantially as 100 described. 105

4. The combination, with the reciprocating plunger of a hay-press, of a horizontal revolving bar or sweep, a lever, J^2 , pivoted concentrically with said bar or sweep and provided with a pin or stud, j , a spring-detent, M , upon 110 the sweep engaging the stud, a stationary cam-surface engaging the detent M for releasing it from the stud, a block, O , movable concentrically with the pivotal axis of the sweep and connected with the lever J^2 , a second 115 spring-detent, N , upon the sweep engaging the said block, a stationary cam-surface engaging said detent N , and connecting devices between the lever J^2 and the plunger, substantially as described. 120

5. The combination, with the reciprocating plunger of a hay-press, of a revolving bar or sweep, a lever, J^2 , pivoted concentrically with said bar or sweep and provided with a pin or stud, j , a spring-detent, M , upon the sweep 125 engaging said stud, a stationary cam-surface engaging said detent M , a block, O , movable concentrically with the pivotal axis of the sweep and connected with the lever J^2 , a second spring-detent, N , upon the sweep engaging the 130 said block, a stationary cam-surface engaging the detent N , and a vertically-arranged lever,

H, connected with the plunger, and a connecting-rod J, and bar J', connecting said lever H with the lever J², substantially as described.

6. The combination, with the reciprocating plunger of a hay-press, of a revolving bar or sweep, a lever, J², pivoted concentrically with said bar or sweep and provided with a pin or stud, j, a spring-detent, M, upon the sweep engaging said stud, a stationary cam-surface 5 engaging said detent M, a movable block, O, curved guides O' for said block arranged concentrically with the pivotal axis of the sweep, a cord connecting said block with the lever J², a guide-pulley for the cord, a detent, N, upon the sweep engaging said block, a stationary cam-surface engaging the detent N, and connecting devices between said lever J² and the plunger, substantially as described.

7. The combination, with the hay-press and plunger, of the sweep L, provided with the spring-detent M, lever J², bar J', pivoted to said lever and connected with the plunger, and the detent P, applied to hold said bar from backward movement, substantially as described.

8. The combination, with the hay-press and plunger, of the sweep L, provided with the

spring-detent M, the lever J², the bar J', pivoted to said lever and connected with the plunger, and the detent P, applied to hold the bar 30 from backward movement, said sweep being provided with a projecting part or stop, p', engaging the detent for releasing the latter, substantially as described.

9. The combination, with a hay-press mounted upon wheels and provided with a reciprocating plunger and inclined arms Q², rigidly attached to the press, of a horse-power driving-gear comprising a frame, C', resting upon the ground, a connecting-rod, J, transmitting 35 motion from the driving-gear to the press, and a brace between the press and the frame C', comprising side pieces, Q', resting upon the ground and engaging the frame, and the arms Q², and planking q, connecting said side pieces 40 and located over the connecting-rod J, substantially as described.

In testimony that I claim the foregoing as my invention I affix my signature in presence of two witnesses.

AXEL GORD.
